UNITED STATES PATENT OFFICE

2,500,984

JOURNAL WIPER

William M. Gewin, Dupo, Ill.

Application September 22, 1944, Serial No. 555,229

8 Claims. (Cl. 308—89)

1

This invention relates to a journal wiper, and concerns itself more particularly with journal wipers adaptable for use in the journal boxes of railway rolling stock.

In the construction of railway cars, it is standard practice to extend the wheel axes into journal boxes in which the ends thereof, shaped in the form of journals, are enclosed. The journal box forms a housing for the journal and the bearing plate through which the weight of the car is transmitted to the axle. The lower part of this box provides a well in which lubricants are contained and in which waste material is inserted as a wick for carrying oil from the well to the under surface of the journal. Due to the construction of these boxes, it is impossible to keep them free from dirt, grit, and other foreign bodies which enter into the oil and are carried up and in between the journal and its bearing. The journals are thus inherently subject to bearing failures due to the abrasive effects of such foreign material. They are also subject to a condition known to the railroad art as "waste grab," which is caused by the journal's carrying the waste from the bottom of the box up to and in between the journal surfaces and the bearing. In this restricted position, the oil is soon worn from the waste, and the latter forms a hard carbon-like deposit on the bearing surface which ultimately results in a bearing failure. Both of these conditions prevent proper lubrication of the car's journals, and cause "hot boxes."

It is known that many waste-retaining devices and journal wipers have been proposed to overcome the aforesaid difficulties, but, for the most part, they have had limited success due to the fact that their installation is complex and requires some operation upon the journal, waste or the device itself for their mounting. In the present invention, it was found possible to perfect a wiper which sacrifices none of its quality performance in preventing grit and waste from reaching the journal bearing at the expense of being readily mountable. On the contrary, the location of the blades of this wiper insures adequate protection for, and the proper lubrication of, the bearing, and its simplicity of construction makes it possible to install the same on any standard journal by simply opening the journal box lid and slipping the wiper into position on the journal.

Accordingly, it is the principal aim of this invention to provide a journal wiper which is positive in its action and which may be easily installed on, or removed from, a journal.

2

It is also an object of the invention to provide a journal wiper, meeting the foregoing requirements and possessing those advantages, which is of simple design and which is economical to construct.

A specific object of the invention is to provide a journal wiper having a pair of wiping blades adapted to be inserted into the box to lie against opposite sides of the journal above a horizontal diameter therethrough, and a separate spring clamping means to hold the blades resiliently in place.

Other objects and advantages of the invention will become apparent as the description proceeds.

In carrying out the invention in its preferred form, a pair of longitudinally extending wiper blades is arranged to be pressed against the journal's surface at points above its horizontal diameter and adjacent to the bearing plate. These blades, which occupy positions on opposite sides of the journal, are held in place and urged into engagement with the journal by means of a yieldable member in the form of a U-shaped spring disengageably connected to the blades. Portions of this spring are also fashioned into loops or hooks that fit around the lugs of the bearing plate and hold the entire wiper assembly in position.

A more comprehensive understanding of the invention will be afforded from the following detailed description when considered in conjunction with the accompanying drawing, in which like reference numerals have been used throughout to designate like parts, and in which:

Figs. 1 and 2 are a side and end view, respectively, of a wiper blade employed in the present invention;

Figs. 3 and 4 are a plan and side view, respectively, of the yieldable member used to hold the wiper blades in place and into engagement with a journal on which the wiper is mounted;

Figs. 5 and 6 are, respectively, a plan and side view of a journal and bearing plate assembly showing the improved wiper mounted thereon;

Fig. 7 is an end view of said journal and bearing plate assembly, partly in section, further illustrating the position and manner of mounting the wiper; and

Fig. 8 is a detailed view illustrating the disengageable connection between the blades and the yieldable member of the wiper.

As illustrated in Figs. 1-4 of the drawing, the improved wiper consists of two wiper blades 11, 55 taking the form illustrated in Figs. 1 and 2, and

a single yieldable member 12, shown in Figs. 3 and 4, which is employed to hold the blades 11 in place against the journal as viewed in Fig. 7. The blades 11 are formed of suitable metal and are sufficient in length to extend the full dimension of the journal. They are shaped to present to the journal surface a bearing edge 13 and a wiping edge 14. Each blade is provided with a notch 15 in which the lips 16 of the member 12 are insertable for holding the blades in their respective places with reference to the journal.

The member 12 is formed from a single length of spring steel and takes the form of a U-shaped spring, as illustrated in Fig. 3. It will be noted, Fig. 4, that this member is bent to form the arms 17 and 18 which support the wiper blades 11 in position. The end section of member 12 is so formed as to pass around the end of the journal. It carries a wearing plate 19 which is centrally located thereon whose function will be discussed later.

As previously stated, the arms 17 and 18 of the member 12 are bent to form the lips 16, which, in turn, enter into the notches 15 of the blades 11, as illustrated in detail in Fig. 8. The continuations of the end sections of the wire forming the arms 17 and 18 are then bent underneath these arms and extend longitudinally thereof to a point intermediate their ends and the base of the U. Here they are turned outwardly, bent vertically upward, and thence horizontally to form the loops or hooks 21 and 22.

When mounted on a journal and bearing plate assembly, the wiper occupies a position with respect thereto, as shown in Figs. 5 and 6. With particular reference to Fig. 6, it will be noted that the blade 11 extends the length of the journal and occupies a position immediately underneath the lower surface 23 of the bearing plate or "brass" 24. The yieldable member 12, which supports the blades 11, occupies a position with respect to these blades which is substantially in a plane common thereto. Its respective arms 17 and 18 engage the blades 11 at the notch 15, as previously described; and the hook sections 21 and 22 thereof encompass the bearing plate lugs 25 and 26, respectively. This method of mounting holds the blades 11 in place and the spring action of the member 12 urges them into contact with the journal 27 in a manner such that the respective wiping surfaces 14 of the blades 11 prevent any grit or foreign matter from reaching the surface 28 (Fig. 7), common to the journal 27 and the babbited surface of the bearing plate 24. The presence of the blades 11 also eliminates any possibility of waste being carried into this space, and at the same time allows more waste to be in contact with the journal, resulting in better lubrication.

The journal wiper assembly comprehended in the above described and preferred embodiment is capable of being installed without any operation on the journal, such as jacking up the bearing plate from the journal or taking the oil and waste out of the box. Here, by the simple expediency of opening the journal box lid (not shown), the blades 11 are positioned and held with one hand directly underneath the overhanging edges 23 of the bearing plate 24, and the yieldable member 12 is carried over the end of the journal in a manner such that the lips 16 are engaged in the notches 15 of the plates. The yieldable member is pushed rearwardly until the hook sections 21-22 clasp the bearing plate lugs 25 and 26 and anchors the entire assembly in fixed position. The wear-

ing plate 19, which is carried on the yieldable member and frictionally held in place, is then pressed against the end of the journal 27 to prevent any part of the member 12 from coming in contact with the rotating journal where it would be subject to wear.

It is a distinctive feature of this invention that it is constructed so as to be separable into three parts, which makes installation possible without disassembly of the journal parts, and also provides for replacement individually of worn parts, although certain features of this invention are applicable to a unitary wiper device wherein all three parts are permanently joined.

15 While it is not intended to limit the invention to the use of any particular material or to any specific size or dimension of any component part thereof, it has been found in successfully practicing the invention that the blades 11 may be made from 18 gauge sheet brass, and the spring member 12, from $\frac{1}{8}$ inch round steel.

20 As many modifications of the invention are possible without departing from the scope thereof, it is to be understood that the description and 25 illustrations herein made are for the purpose of presenting an embodiment of the invention only and are not to be considered in a limiting sense.

What is claimed is:

1. In a journal wiping device, the combination 30 of a pair of wiping blades each being shaped to present a bearing surface and a wiping surface to a journal and arranged to extend longitudinally of and in engagement with the opposite sides thereof, and a yieldable means for holding said 35 blades in position and urging the same toward each other, said yieldable means being loosely connected to said blades for instant release and comprising a resilient member formed for disposition about the end of a journal and for insertion 40 into an assembled journal box, said resilient member being operatively connectible to said blades after insertion of the latter into an assembled journal box.

2. A journal wiping device, comprising the 45 combination of a pair of members arranged to extend longitudinally of and in engagement with opposite sides of a journal at a point above its horizontal diameter, spring means for urging said members toward each other, and into contact 50 with said journal, and a member depending from said spring means and engageable with the end of a journal to prevent contact of the spring means with a journal to avoid wear of the spring means.

55 3. A journal wiper comprising, in combination, a pair of wiper blades adapted to be disposed along opposite sides of a journal below the ends of the bearing plate, said blades being substantially coextensive with the journal with which it is associated and engageable therewith above the horizontal diameter thereof, and a spring means for applying a clamping force to maintain the wiper blades against the journal, said spring means being generally U-shape and having a bight portion adapted for disposition across the end of a journal above the lubricant well and having arms bent from the bight portion and adapted to extend across the flange of a journal 60 to the wiper blades, said arms being yieldably and readily removably connected with the wiper blades and urging them inwardly against a journal when the wiper is operatively mounted by a clamping force applied above the horizontal diameter of the journal, each arm including a 65 70 75

hook portion for engagement with the usual lug of a journal brass.

4. A journal wiper comprising, in combination, a pair of wiper blades adapted to be disposed along opposite sides of a journal substantially coextensive therewith and below the ends of the bearing plate, said blades being engageable with a journal above the horizontal diameter thereof, and a spring means for applying a clamping force to maintain the wiper blades against a journal, said spring means comprising a unitary generally U-shaped spring wire member having a bight portion adapted to extend across the end of a journal and beyond the flange thereof and arms extending from the bight portion, said arms being adapted to extend around the end flange and along the sides of a journal to approximate midpoints of the wiper blades and being releasably connected therewith the blades, said arms being bent back from beyond said connection points toward the bight and then bent upwardly and then horizontally to provide supporting hooks to clamp over the usual lugs on a journal brass to hold the device in place.

5. A journal wiper blade comprising an elongated plate having a journal wiping edge, the portion of the plate adjacent said edge being disposed out of the plane of the main portion of the plate, the other edge portion of the plate being returned towards the wiping edge and comprising a bearing surface formed to receive the major holding force when the blade is disposed on a journal.

6. A journal wiper blade comprising an elongated plate having a journal wiping edge, the portion of the plate adjacent said edge being disposed out of the plane of the main portion of

the plate, the other edge portion of the plate being returned towards the wiping edge and comprising a bearing surface formed to receive the major holding force when the blade is disposed on a journal, said plate including a centrally disposed notch for receiving a supporting arm.

7. A journal wiper blade comprising an elongated plate having a journal wiping edge, the other edge portion of the plate being returned towards the wiping edge and comprising a bearing surface formed to receive the major holding force when the blade is disposed on a journal.

8. A journal wiper blade support comprising a U-shaped resilient member for urging removable blades into engagement with a journal including a pair of arms each including lips for releasable connection with a journal wiper blade, and a hook-like member forming a part of each arm bent to conform with and to grasp a bearing plate lug.
